APPARATUS FOR PRODUCING FROM END-
LESS FIBERS A CARD SLIVER SUITABLE
FOR DRAWING

Karl Josef Schmitt, Chemnitz, Germany, assignor to Sächsische Textilmaschinenfabrik vorm. Rich. Hartmann Aktiengesellschaft, Chemnitz, Germany, a corporation

Application December 24, 1938, Serial No. 247,700
In Germany February 5, 1938

4 Claims. (Cl. 19—1)

This invention relates to a method of producing from endless artificial fibers a continuous card sliver suitable for drawing.

Various methods have been proposed for this purpose but in practice they possess more or less objections or are entirely impracticable.

According to one of the known proposals the fibers of the sliver are cut by a cutting cylinder with narrow mutually displaced knives in such a manner that the pieces of fiber, owing to the cuts distributed over the width of the sliver, preserve a certain cohesion. Owing to the smooth cut surfaces of the sliver pieces it is, however, not possible to shift the fibers separately and successively in a drawing apparatus but the pieces of the sliver as such are shifted. The sliver leaving the drawing apparatus consequently is of very unequal thickness so that several doublings are necessary to obtain the necessary uniformity.

For the purpose of avoiding the above mentioned disadvantages the endless sliver is pierced, according to the invention, by means of needles or the like in such a manner that the fibers are cut individually or almost individually, the sliver being held taut at the cutting point by pairs of rollers or the like.

An apparatus for carrying out the invention is illustrated, by way of example, in the accompanying drawing in which:

Fig. 1 shows the apparatus in side elevation, Fig. 2 is a front view thereof.

The artificial fibers fed in an endless sliver from the artificial silk spinning machine are stretched between two pairs of rollers *a* and *b*. Above this point a comb *d* is arranged which is vertically guided and moved up and down by a shaft *e* through the intermediary of an eccentric *f*. The needles of the comb *d* are of such shape, that they cut the fibers as far as possible individually or approximately individually. The space between the piercing point and the clamping point of the pair of rollers *b* is smaller than the length of staple.

To enable the needles to pierce the sliver at points distributed over the entire width, the comb *d* is shifted after each stroke a very short distance ($1\frac{1}{100}$ to $\frac{3}{100}$ of a millimetre), by means of a cam *g* which is driven from the shaft *e* through the intermediary of a worm gear *h*. The cam *g* preferably formed of spirals, firmly bears against the surface *k* under the influence of a spring *i*, so that the shaft *e* is shifted in lateral direction together with the comb *d*. This is effected very gradually, the piercing operations of the comb

taking place in very rapid succession. Owing to the step at the end of one of the spirals of the cam, the comb is precipitately returned to the right into its initial position, under the influence of the spring *i*, as soon as the lateral movement 5 imparted to the comb by the spiral is terminated. The ratio between the comb movement and that of the sliver movement must be chosen according to the desired length of staple.

It is advantageous, to support the sliver in 10 closest proximity to the piercing points, that is between the pairs of rollers *a* and *b*, by a table *m* provided with a notch or recess, so that stretching of the fibers is avoided during the cutting operation or can only take place in di- 15 rect proximity to the piercing point.

On the outer side of the pair of rollers *b* another pair of rollers *c* is arranged, these rollers being driven at a higher speed than the rollers *b* and serving to tear the fibers which are not separated by the comb *d*.

The needles of the comb may be blunt, very sharp, serrated, hook-shaped or similarly shaped.

The slivers delivered from several apparatus of the type described are doubled and stretched 25 in a normal drawing frame and condensed at *o*, by a revolving tube or roller rubbers and finally formed into a lap *p*.

I claim:

1. An apparatus for producing from endless 30 fibers a sliver suitable for drawing, comprising in combination two pairs of sliver stretching rollers, a comb vertically reciprocated between said pairs of rollers to pierce the sliver stretched between said rollers, and means for laterally shifting said comb after every effective stroke.

2. An apparatus for producing from endless fibers a sliver suitable for drawing, comprising in combination two pairs of sliver stretching rollers, a comb vertically reciprocated between said 40 pairs of rollers to pierce the sliver stretched between said rollers, a cam disc formed by at least one spiral race bearing against said comb and adapted to gradually displace the same laterally after each effective stroke, and means for precipitately returning said comb into its initial position at the end of its lateral displacement.

3. An apparatus for producing from endless fibers a sliver suitable for drawing, comprising in combination two pairs of sliver stretching rollers, 50 a comb vertically reciprocated between said pairs of rollers to pierce the sliver stretched between said rollers, and means for laterally shifting said comb after every effective stroke, the distance between the second pair of rollers and the pierc- 55

ing point being shorter than the desired length of staple.

4. An apparatus for producing from endless fibers a sliver suitable for drawing, comprising in combination two pairs of sliver stretching rollers, a comb vertically reciprocated between said

pairs of rollers to pierce the sliver stretched between said rollers, means for laterally shifting said comb after every effective stroke, and a table under said comb adapted to support the sliver in proximity to the piercing point.

KARL JOSEF SCHMITT.
